UNITED STATES PATENT OFFICE.

TALBOT LENNOX, OF MARSHALLTOWN, IOWA.

HANDLE FOR METAL BASKETS.

Application filed September 13, 1921. Serial No. 500,462.

To all whom it may concern:

Be it known that I, TALBOT LENNOX, a citizen of the United States, and a resident of Marshalltown, in the county of Marshall 5 and the State of Iowa, have invented a certain new and useful Handle for Metal Baskets, of which the following is a specification.

The objects of my invention are to provide simple, durable and inexpensive means for connecting together the ends of a rope and for securing same to a basket or the like in such a manner as to provide a convenient 10 and efficient handle which has a free pivotal movement with relation to the basket.

My invention consists in the construction, arrangement and combination of the device for holding together the ends of the rope handle and a clip for pivotally supporting 20 said device and attaching same to a basket or the like whereby the objects contemplated are attained, as hereinafter more fully set forth, pointed out in my claims, and illustrated in the accompanying drawings, in 25 which:

Figure 1 shows a side elevation of a part of a metal basket having my improved handle applied thereto.

Figure 2 shows an enlarged detail sectional view on the line 2—2 of Figure 1.

Figure 3 shows an enlarged side view of a handle detached from a basket and from the handle holding clip, to illustrate the device for fastening the ends of the rope together.

Figure 4 shows a sectional view on the line 4—4 of Figure 3.

Figure 5 shows a detail side view illustrating a part of the device for holding the ends of the rope together.

Figure 6 shows a sectional view on the line 6—6 of Figure 1.

Referring to the accompanying drawings I have used the reference numeral 10 to indicate that part of the sheet metal basket 45 shown. The top edge of the basket is provided with enlarged rounded bead 11.

The body portion of my improved handle is formed of a single piece of rope 12 with its ends brought together, thus forming a 50 loop. I have provided a device for holding together the ends of the rope, and at the same time forming a pivotal bearing for attaching the ends of the rope to the metal basket as follows:

55 Numeral 13 indicates a metal cylinder with its edges brought adjacent to each other

as shown in Fig. 3. Near each end of the cylinder 13 I have formed in the outer surface a groove or depression 14 extending partly around the cylinder. In line with 60 said grooves, and adjacent to the edges of the cylinder, I have formed, from the metal of the cylinder itself, the outwardly extending loops 15. In each of the grooves 14 I have provided a split ring 16 made of relatively heavy wire, the end portions of which are extended through the loop 15, and the part that projects through said loops is preferably beveled or inclined at 65 17.

In assembling the handle, the adjacent 70 edges of the cylinder 13 and the split rings 16 are, as first constructed, separated far enough to permit the rope ends to be readily inserted in the cylinder, and they are preferably extended into the cylinder until the 75 inner ends meet, as clearly shown in Figure 2. Then the two split rings 16 are forced towards each other with the result that when their pivotal end portions engage, these end portions will be bent outwardly away from 80 each other as clearly shown in Figure 3, thus securely holding together the edges of the cylinder 13.

Furthermore, the parts of the cylinder 13 adjacent to the depression 14, in other words, 85 the inwardly extending ribs that are formed by the depression 14, will be forced into the rope at points spaced apart from the ends of the rope to such extent as to bind the ends of the rope together firmly enough to prevent separation under any of the conditions 90 to which the devices of this class are ordinarily subjected.

For securing the device to a basket or the like, I have provided sheet metal clips. The 95 outer side of this clip designed to lie against the outer surface of the basket, is formed at its lower end with a flat portion 18, and above this is an outwardly extending semi-cylindrical portion 19. In this semi-cylindrical portion near its ends are the outwardly extending ribs 20. The top is formed into a loop 21 to pass over the bead 11 at the top of the basket, and the inner side is formed flat at 21 to lie against the inner surface of the basket, then the entire device is firmly secured to the basket by means of two rivets 22 extending through the lower portion of the clip and also through the basket itself. The relative proportions of these portions are such that the split ring 16 and the loops 15 of the handle member enter the cir- 105 110 115

circular grooves on the inside of the clip member formed by the ribs 20, in such a manner as to prevent longitudinal movement of the cylinder 13 relative to the clip, and at the 5 same time permit free circular movement of the cylinder 13 within the clip.

In practical use, it is obvious that the device is of very simple and inexpensive construction and may be made and assembled 10 mainly by automatic machinery and without hand work. The rope may be previously cut to the desired length then the ends of the rope may be brought together and placed within the expanded cylinder which is made 15 with its sides separated far enough to freely admit the rope ends. When this has been done, a powerful pressure is applied to the split rings tending to bring their ends together and also to bend over the ends to lock 20 the parts firmly together. By this arrangement, it is obvious no extra movement is required for locking together the ends of the split rings after sufficient pressure has been applied to bring their ends together and to 25 firmly clamp the rope within them.

In applying the handles thus made to the basket, it is only necessary to place the cylindrical portion of the handle in the semi-cylindrical recess of the clip and then place 30 the clip against the basket and bend the inner portion of the clip against the inner face of the basket, and finally rivet through the lower end of the clip and the basket. When this has been done the annular ribs 35 on the cylindrical part of the handle and the annular grooves on the interior of the clip will perform the two functions of positively preventing longitudinal movement of the rope, and at the same time freely permitting a hinged or pivotal movement of the 40 rope.

I claim as my invention:

1. In a handle of the class described, the combination of a loop shaped grip portion, 45 a metallic connecting member designed to receive the ends of the grip portion, two open rings applied to the connecting member near its ends and designed when closed to force the connecting member firmly against the 50 grip member to prevent movement of its ends relative to each other.

2. In a handle of the class described, the combination of a loop shaped grip portion, a metallic connecting member designed to receive 55 the ends of the grip portion, two open rings applied to the connecting member near its ends and designed when closed to force the connecting member firmly against the grip member to prevent movement of its ends 60 relative to each other, and also to form annular ribs on the exterior of the connecting member, and a clip member for fastening the handle to an article, said clip member hav-

ing grooves to receive said annular ribs and to permit rotary movement and to prevent 65 longitudinal movement.

3. In handle, the combination of a rope and a connecting member, the latter being made of cylindrical form and open on one side and having annular depressions near 70 its ends, and two open rings in said annular depressions, said connecting member being so arranged that the rope ends may be easily inserted in it and then when the open rings are forced together the annular depressions 75 will be forced into the rope by said rings and the connecting member will be firmly held in position by the rings.

4. In a handle, the combination of a rope, a sheet metal connecting member cylindrical 80 in form and open at one side and having annular depressions near its ends, and also having a part arched over each depression and an open ring in each of said depressions, a part of the ring being extended through 85 said arched portion and held thereby in the annular depression, said parts being so arranged that when the open rings are forced together the annular depressions will be forced into the rope and said parts will 90 be firmly held together by the rings.

5. In a handle, the combination of a rope, a sheet metal connecting member cylindrical in form and open at one side and having annular depressions near its ends, and also having 95 a part arched over each depression and an open ring in each of said depressions, a part of the ring being extended through said arched portion and held thereby in the annular depression, said parts being so arranged 100 that when the open rings are forced together the annular depressions will be forced into the rope and said parts will be firmly held together by the rings, the ends of said open rings being beveled or inclined in such manner that when they are forced toward each other they will engage each other and be bent laterally for the purpose as stated. 105

6. In a handle device, the combination of a loop-shaped grip member, a connecting 110 member of cylindrical form, having the ends of the grip member secured therein and having annular ribs extending outwardly at its end portions, and a clip designed to be passed over the edge of the basket and to be 115 firmly secured thereto, and having at one of its sides a rounded portion to extend outward from the basket and designed to receive in it the said cylinder connecting member, and also provided with grooves on its 120 interior to receive the said annular ribs, thereby permitting free rotary movement and preventing longitudinal movement of the connecting device within the clip.

Des Moines, Iowa, February 5, 1921.
TALBOT LENNOX.
